GRINDER

Filed Nov. 5, 1923

2 Sheets-Sheet 2

UNITED STATES PATENT OFFICE.

ALBERT F. FROUSSARD, OF ST. LOUIS, MISSOURI.

GRINDER.

Application filed November 5, 1923. Serial No. 672,868.

To all whom it may concern:

Be it known that I, ALBERT F. FROUSSARD, a citizen of the United States, residing at the city of St. Louis, in the State of Missouri, have invented certain new and useful Improvements in Grinders, of which the following is a specification.

This invention relates to grinders for polishing the internal cylindrical surfaces of internal combustion-engines and the like, and pertains more particularly to improvements in that type of grinder which forms the subject-matter of my prior application for patent, Serial Number 627,267, filed 15 March 24, 1923.

One of the objects of the present invention is to provide improvements in the grinder head, which will simplify its manufacture and materially lower the costs of 20 its production.

Another object is to provide a novel means for extending the abrasive blocks diametrically, thereby adapting a single size grinder to cylinders of widely varying diameters, 25 and, also, enabling the use of the abrasive blocks after they have become worn to such a degree that ordinarily they would have been discarded.

A further object is to provide a novel 30 means for coupling an extension or lengthening rod to the grinder-head shaft or spindle.

Other objects and advantages will appear as the description proceeds.

In the accompanying drawings forming 35 part of this specification, in which like numbers of reference denote like parts wherever they occur,

Figure 1 is a transverse section taken on 40 the line 1—1 of Figure 2;

Figure 2 is an elevation of the complete 45 grinder and extension rod;

Figure 3 is a transverse section taken on the line 3—3 of Figure 2;

Figure 4 is a transverse section taken on 50 the line 4—4 of Figure 2;

Figure 5 is a transverse section taken on the line 5—5 of Figure 2;

Figure 6 is a longitudinal central section, 55 taken perpendicularly to Figure 2;

Figure 7 is a transverse section taken on the line 7—7 of Figure 6;

Figures 8 and 9 are fragmentary front and side elevations, respectively, showing an 60 extension applied to an abrasive block; and

Figure 10 is a transverse section taken on the line 10—10 of Figure 8.

A vertical spindle 1 consists of an upper portion 2 of hexagonal cross-section, an intermediate cylindrical portion 3, a portion 4 of square cross-section near its lower extremity, a cylindrical portion 5 between portions 2 and 3, and cylindrical portions 6 immediately adjoining the square portion 4 at each of its ends. Rectangular retainer 7 for abrasive block 8 are formed, each of a single piece of sheet metal, bent to a channel shape, having two parallel side walls 9, connected by a perpendicular inner wall 10, and having an open outer side 11, restricted by inwardly extending flanges 12, projecting perpendicularly from the side walls 9. The retainers 7 have 45 degrees bevels 13 on their inner edges, and are secured to the square portion 4 of the spindle 1 by screws 14, fitting tapped holes 15 in the portion 4, the beveled edges 13 of the several retainers 7 being in contact with one another, whereby they mutually retain one another against angular movement about the screws 14. The cylindrical portions 6 are of smaller diameter than the square portion 4 and have external threads 16 for the reception of nuts 17. A cylindrical shell 18, having a bottom wall 19, containing a concentric cylindrical aperture 20, for the reception of the upper of the cylindrical portions 6, is clamped between upper nut 17 and shoulder 21, forming the upper terminus of portion 4. The lower face of wall 19 is provided with projections 22 and depressions 23. The projections 22 fit closely between the retainers 7, whose ends are held within the depressions 23. A plate 24, containing a concentric cylindrical aperture 25, for the reception of the lower of the cylindrical portions 6, is clamped between lower nuts 17 and shoulder 26, forming the lower terminus of portion 4. The upper face of plate 24, also, has projections 22 and depressions 23, which function similarly to those on shell 18 to engage the lower end of the retainers 7. Shell 18 and plate 24 close the open ends of the retainers 7, and prevent longitudinal movement of the blocks 8. Shell 18 is adapted to contain kerosene or other lubricant, which is exuded through ports 27 by centrifugal force when the grinder is in rapid rotation. A cap 28, having an opening 29, for the passage of the

spindle 1, is secured to the shell 18 by screws 30. Lubricant is supplied to the interior of shell 18 through an opening 31 in cap 28, the said opening 31 being tapped and 5 normally closed by a screw 32. Blocks 8 of any suitable abrasive material, such as crystolendum, emery, carborundum, and the like, fit in the retainers 7, and have flanges 33, which contact with the flanges 12 of the 10 retainers 7 and thereby limit the outward movement imparted to said blocks by compression springs 34, interposed between each pair of diametrically opposed blocks 8 and held in passages 35 in the spindle 1 and 15 corresponding-passages 36 in the inner walls 10 of the retainers 7. The blocks 8 are protected from the cutting action of the springs 34 by shields 37 interposed between said spring 34 and blocks 8. The shields 37 are 20 preferably formed of sheet metal and have perpendicular projections or tits 38. The blocks 8 can be withdrawn from the retainers 7 at the lower end after plate 24 has been removed, but the shields 37 are retained 25 in the retainers 7 by the engagement of the tits 38 with the springs 34. The blocks have rounded grinding surfaces 39, which conform to the internal surfaces of the cylinders to be ground.

30 To enable the grinder to accommodate a wider range of cylinder diameters, extensions 40 for the blocks 8 are provided, as shown in Figures 8, 9, and 10. These extensions are preferably formed of sheet 35 metal and consist substantially of two side walls 41 connected by an inner wall 42. The side walls 41 are bent outwardly at their inner ends to form flanges 43, which contact with the flanges 12 of the retainers 7, 40 and thereby limit the outward movement of said extensions by the action of the compression springs 34. The free ends of the walls 41 are bent to form channels 44, adapted to receive the flanges 33 of the 45 blocks 8, and prevent transverse movement of the blocks 8 with respect to the extensions 40. The extensions 40 are of the same length as the blocks 8, except at the channels 44, which project beyond the ends of 50 the extensions 40 to receive the cross-member 45 and tube 46. Cross-member 45 has shoulders 47 formed by reducing the ends 48, which extend through holes 49 in the channels 44, and are peened over against 55 the outside of the channels 44, rivet fashion, clamping the channels 44 against the shoulders 47. A screw 50 passes through holes 51 in the other ends of the channels 44 and through spacing tube 46, and is provided with a nut 52, which is screwed against 60 the outside of one of the channels 44, and thereby clamps the said channel against the end of the tube 46, and the other channel between the head 53 of the screw 50 and 65 the other end of the tube 46. Both cross-

member 45 and screw 50 strengthen and stiffen the extension 40, and, also, serve as stops to prevent longitudinal movement of blocks 8 in extensions 40, cross-member 45 forming a permanent connection and screw 50 a removable connection to permit removal of block 8 for replacement or other reasons. Extensions 40, also, prolong the useful life of the abrasive blocks 8, by enabling them to be extended after they have become worn to such an extent that ordinarily they would have to be discarded.

The cylindrical portion 5 of spindle 1 is of smaller diameter than the portion 3, forming a shoulder 54. A pin 55 passes transversely through part 5, and is secured therein by a tight fit, its ends projecting therefrom at diametrically opposite points. In grinding the cylinders of certain types of engines, it occurs that the spindle 1 is of insufficient length to enable the grinder head to reach the bottom of the cylinder, and an extension or lengthening rod 56 must be employed, as shown in Figures 2, 6, and 7, the socket of the motor shaft being connected to the hexagonal shaped end 57 of the rod 56, instead of directing to the hexagonal portion 2 of the spindle 1, as is usual, when the extension 56 is not used. The cylindrical portion 58 of rod 56 has a concentric cylindrical recess 59 at its lower end, forming a tubular portion 60 to receive portions 2 and 5 of the spindle 1. The lower end of tubular portion 60 is split at diametrically opposite points by longitudinally-extending slots 61, having their upper ends communicating with slots 62, which extend from slots 61 in a counter-clockwise direction and at a slight incline from the horizontal, looking from the top of the rod 56. In connecting rod 56 to spindle 1, portion 60 is brought directly over spindle 1 and pushed down, so that the projecting ends of pin 55 pass into the slots 61, until the pin 55 abuts against the top edges of the slots 62, after which rod 56 is rotated in a clockwise direction, causing the tongues 63 to become wedged between shoulder 54 and the projecting ends of the pin 55, whereupon rod 56 and spindle 1 rotate as one unit in a clockwise direction, but become disengaged upon reversing the direction of rotation.

The depth of travel of the grinder in the cylinder is limited by a safety stopping plate 64, adapted to engage the end of the cylinder and thereby prevent damage to the honer by running the same below the bottom of the cylinder. Plate 64 can be set on shank 11 to accommodate different lengths of cylinders by a headless set screw 65.

Having thus described this invention, I hereby reserve the benefit of all changes in form, arrangement, order, or use of parts, as it is evident that many minor changes may be made therein without departing

from the spirit of this invention or the scope of the following claims.

I claim:

1. In a grinder the combination of a rotating head having a plurality of plane sides in its periphery, and a plurality of retainers secured to the said sides, the said retainers each consisting of a base plate on the said sides, and side plates extending perpendicularly from the said base plate and connected thereby, there being beveled outer faces at the base of said side plates, the said retainers being arranged contiguously to one another with the said beveled faces forming their common meeting faces, and abrasive blocks removably carried by said retainers.
2. In a grinder, the combination of a spindle having a squared portion provided with crossed pairs of transverse passages, a retainer removably secured to each face of the squared portion of the spindle and having passages registering with one pair of the transverse passages in the spindle, an abrasive block longitudinally removably positioned within each retainer, axially adjustably means carried by the spindle for holding said blocks against removal, means in said pairs of registering passages for forcing said blocks radially outwardly, and means carried by said retainers and blocks for restricting the radial movement of the latter.
3. In a grinder, the combination of a rotating head having a plurality of plane

sides in its periphery, a plurality of retainers secured to the said sides, the said retainers each consisting of a base plate on the said sides, and side plates extending perpendicularly from the said base plate and connected thereby, there being beveled outer faces at the base of said side plates, the said retainers being arranged contiguously to one another with the said beveled faces forming their common meeting faces, and abrasive blocks removably carried by said retainers.

4. In a grinder, the combination of a rotating head provided with a plurality of plane sides in its periphery, a plurality of retainers secured to the said sides, the said retainers each consisting of a base plate on the said sides, and side plates extending perpendicularly from the said base plate and connected thereby, there being beveled outer faces at the base of said side plates, the said retainers being arranged contiguously to one another with the said beveled faces forming their common meeting faces, abrasive blocks carried by the said retainers, means for forcing said abrasive blocks radially outwardly of the rotating head, and means for preventing the blocks from accidentally being disconnected from the retainers.

In testimony whereof I hereunto affix my signature.

ALBERT F. FROUSSARD.
